EARL M. HILL, OF WISCONSIN RAPIDS, WISCONSIN, ASSIGNOR TO CONSOLIDATED WATER POWER & PAPER COMPANY, OF WISCONSIN RAPIDS, WISCONSIN, A CORPORATION OF WISCONSIN.

CORE TIP.

Application filed October 12, 1925. Serial No. 62,096.

This invention relates to core tips for winding cores of rolls of paper, such as commonly used in newspaper printing.

Numerous efforts have been made to protect the ends of the tubular core, which is usually formed of paper rolled and pasted together. Metal tips have been suggested for this purpose having the keyway formed therein in various manners to avoid the 10 wearing of the core by the engagement of the driving dog therewith both during the winding and unwinding operations. The cores are used repeatedly and protection of this sort is essential. Protection must also 15 be afforded against the spreading of the ends of the tubular core by the use of pry bars inserted therein for moving the very heavy roll of paper wound thereon and such protecting tip should be devoid of shoulders on 20 the inside that might be engaged by a shaft or bar passing through the core, and devoid of shoulders on the outside to not interfere with the paper wound on the core. In most instances the metal core tips have required 25 the paper core to be materially weakened by having its ends trimmed to receive the metal tip and by reason of openings formed therein to take rivets, screws and the like.

It is an object of the present invention to 30 avoid the weakening of the core in this manner by providing a substantial core tip with flaring flanges capable of being forced onto the end of the core and compressing the core material between them to effect a tight joint 35 making other fastening means unnecessary and sufficiently embedding the flanges in the core material to cause them to lie substantially flush with the inner and outer surfaces of the core.

Another object of the invention is to produce the keyway in such a core tip that will have its edges re-enforced or braced by hemming or turning the edges of the metal at 45 the opening without materially reducing the thickness of the metal as when the core seat is formed by indenting without cutting the metal.

With the above and other objects in view 50 the invention consists in the core tip as herein claimed and all equivalents.

Referring to the accompanying drawings in which like characters of reference indicate the same parts in different views,

Fig. 1 is an end view of a core tip constructed in accordance with this invention; 55

Fig. 2 is a sectional view thereof in place on the end of a core tube;

Fig. 3 is a similar sectional view on a plane at right angles to the sectional plane of Fig. 2, and 60

Fig. 4 is a sectional view on the plane of line 4-4 of Fig. 3.

In these drawings, 10 indicates the usual core tube having its end compressed between the inner and outer concentric annular 65 flanges 11 and 12 of the core tip, which are joined by the ring 13. The ring and flanges are integral, being preferably formed up from a disk of cold rolled steel in a manner that is well known in the art. 70

The distance between the parallel flanges 11 and 12 is somewhat less than the thickness of the core tube and the edges of said flanges are formed flaring so as to compress the core tube material between them when 75 the core tip is forced thereon with great pressure. The strength of the core tube material is thus not reduced at the junction with the core tip and still, by reason of the flanges terminating in knife edges 14, they 80 form a close joint therewith free from objectionable shoulders either on the interior or the exterior of the core. This method of attaching the core tip to the end of the core avoids the necessity for rivets or 85 screws or other attaching means that would weaken the joint.

The usual notch or key seat 15 is formed in the edge of the core tube and the core tip is cut away at the inner flange 11 and the connecting ring 13 to give access thereto and to avoid the key engagement with the raw edge of the cut metal such edges 16 of the opening are turned inwardly, as best seen in Fig. 2. The rounded edges of the key opening in the metal tip not only facilitate the engagement of the key in its key seat formed thereby, but afford a strengthening reinforcement for such key seat against tearing or distortion as the result of pressure thereon by the driving key. Inasmuch as the opening is cut in the metal before the edges are turned, such edges are not drawn to materially reduce their thickness and they are consequently stronger and better able to resist tearing and distortion by the key than if 100 105

the keyway were produced by merely indenting without cutting the metal so as to form a key pocket.

The key opening cut in the metal core tip having its edges re-enforced by being turned into the key seat of the core tube without stretching affords a stronger and more durable key-engaging surface and insures a longer life for the core tube.

10. The metal core tip completely filled with the compressed core material is not likely to be expanded and distorted by the centering cones fitting therein and altogether the tubular core equipped with the core tips as described is better adapted for long continued use without the development of defects common to other devices of this character.

What I claim as new and desire to secure by Letters Patent is:

20. 1. A core tube having a metal core tip, the latter being provided with concentric inner and outer integral flanges with their edges flaring and terminating in cylindrical surfaces and having the edge of the core tube forced therein and compressed thereby whereby the core tip is permanently secured to the core tube with the cylindrical surfaces of the flanges flush with the inner and outer walls of the core tube.

30. 2. A core tube having a metal core tip, the latter being provided with concentric inner

and outer integral flanges having their edges flaring and terminating in rigid knife edges flush with the inner and outer surface of the core tube, the end of the core tube being compressed between the flanges.

35. 3. A metal core tip for core tubes comprising a ring having inner and outer concentric integral flanges to receive the end of a core tube between them, there being an opening cut in the ring and the inner flange to constitute a key seat, the edges of said opening being turned inwardly to re-enforce the key seat against splitting or distortion.

40. 4. A core tube having a metal core tip, the latter being formed of an end ring with integral concentric inner and outer flanges having their edges flaring and forming rigid knife edges, the end of the core tube being compressed within the core tip with the knife edges of the flanges flush therewith, there being a key seat notch in the edge of the core tube and a corresponding opening cut in the end ring and the inner flange of the metal core tip, the edges of said opening being bent 45 inwardly within the notch to form a key seat, such bent edges of the opening serving to prevent splitting or distortion of the metal around the key seat.

55. In testimony whereof, I affix my signature.

EARL M. HILL.
